ELECTRIC SWITCH

Filed May 26, 1928

Inventor:
Charles F. Schwennker,
by *Charles E. Tullar*
His Attorney.

UNITED STATES PATENT OFFICE

CHARLES F. SCHWENNKER, OF SCHENECTADY, NEW YORK, ASSIGNOR TO GENERAL ELECTRIC COMPANY, A CORPORATION OF NEW YORK

ELECTRIC SWITCH

Application filed May 26, 1928. Serial No. 280,876.

My invention relates to electric switches and particularly to electric switches of the liquid break explosion chamber type. It is an object of my invention to provide an improved electric switch of this character, the fixed contact of which may be readily removed and reinserted. Another object of my invention is the provision in a switch of this character of improved means of relieving the explosion chamber of a certain amount of gas through the contact supporting studs. Other objects of my invention will appear as I proceed with the detailed description.

My invention will be better understood from the following description taken in connection with the accompanying drawing, and its scope will be pointed out in the appended claims.

In the drawing Fig. 1 shows in longitudinal section a portion of a switch embodying my invention; Fig. 2 is a transverse section taken on the line 2—2 of Fig. 1; Fig. 3 is a perspective view of the construction shown in Fig. 1 drawn to a smaller scale and with the carrier of the fixed contact removed; and Fig. 4 shows the carrier removed.

Referring to the drawing the parts illustrated are arranged to be immersed in an insulating liquid, as for example oil, contained in a suitable vessel through the top of which passes the conducting stud 1 extending through the insulator bushing 2. Secured to the stud 1 is the adapter or contact supporting member 3 which is shaped to adapt a vertical fixed contact to the inclination of the supporting stud. Both the stud and the adapter are shown as being hollow, the central opening therethrough forming a passage 4 for the discharge of gas to the exterior of the enclosing vessel. Through the lugs 5 extending from the sides of the adapter pass bolts 6 having nuts 7 on their upper ends and having their lower ends firmly secured in the flange 8 of the explosion chamber casing 9. In the bottom of this casing is mounted the usual throat bushing through which the movable contact or rod 10 of the switch is adapted to project. The chamber also has the usual lining 11 of insulating material and the exterior insulating shield 12.

The fixed or socket contact 14 which receives the contact rod 10 is preferably segmental in form and is shown provided with garter springs 15 for yieldingly pressing the segments against the rod.

The fixed contact is mounted in the detachable carrier 16 which is shown as having the general form of a frustum of a cone having a height sufficient to permit it being readily moved laterally into position between the adapter and the explosion chamber casing. For convenience in moving the carrier it is shown provided with the handle 17. The lower portion of the carrier is constructed as a separate member 18 and has the curved portions 19 to which an arc drawn from the fixed contacts upon opening the circuit is transferred. The contact carrier 16 thus forms the top of the explosion chamber casing. The adjustable stop screw 21 mounted in a lug on the flange 8 of casing 9 limits the rearward movement of the carrier when the same is pushed into operative position. The carrier 16 is firmly secured in position and in good electrical contact with the adapter by tightening the nuts 7, thus tightly clamping the carrier between the adapter and the explosion chamber casing. To remove the carrier, as for example, to inspect or renew the contacts therein, one need only to loosen the nuts 7 and by grasping the handle 17 withdraw the carrier laterally.

For the purpose of releasing some of the gas produced in the explosion chamber, particularly when the switch is called upon to interrupt a heavy load, I have formed the carrier with the gas discharge passage 25 extending longitudinally through the wall thereof. This passage is shown flared at the lower end in the part 18 and as terminating at the upper end in the recess 26 which communicates with the gas discharge passage 4 extending through the adapter and stud. By this construction a certain amount of hot gas is allowed to escape from the explosion chamber through the fixed contact carrier and stud but is kept out of actual contact with the fixed contact to prevent possible damage being done thereto. The small vent hole 27 in the top of the carrier prevents the interior

cavity becoming air or gas locked and also assists in permitting the escape of oil from the interior when the rod 10 enters the carrier.

5 What I claim as new and desire to secure by Letters Patent of the United States is:

1. An electric switch comprising cooperating fixed and movable contacts separable in an insulating liquid, an insulated contact 10 supporting member, an explosion chamber casing secured to the member in spaced relation thereto, and a contact carrier arranged to slide laterally to a position between the supporting member and the casing, said contact carrier adapted to be maintained in operative position by clamping means common to said supporting member and casing.

2. An electric switch comprising cooperating fixed and movable contacts separable in 20 an insulating liquid, an insulated contact supporting member, an explosion chamber casing secured to the member in spaced relation thereto, and a detachable holder for the fixed contact clamped between the member and the 25 casing.

3. In an electric switch of the liquid break type, a contact supporting member, an explosion chamber casing secured to the member in spaced relation thereto, a laterally detachable fixed contact carrier, and means for clamping the carrier in position between the member and the chamber, whereby loosening of said means is effective to permit lateral removal of the contact carrier.

35 4. In an electric switch of the liquid break type, a contact supporting member having a gas discharge opening therethrough, an explosion chamber casing, and a contact carrier arranged between the member and the casing 40 having a gas passage therethrough connecting at opposite ends with the opening in the supporting member and with the interior of the explosion chamber casing.

5. In an electric switch of the liquid break 45 type, a contact supporting member having a gas discharge opening therethrough, an explosion chamber casing spaced from the supporting member, a detachable contact carrier having a portion forming one end of the explosion chamber casing and means for securing the carrier in position between the supporting member and the casing.

6. In an electric switch of the liquid break 55 type, a contact supporting member having a gas discharge opening therethrough, an explosion chamber casing spaced from the supporting member, and a laterally removable contact carrier clamped between the supporting member and its explosion chamber casing, 60 said contact carrier having a gas discharge passage extending therethrough and connecting at opposite ends with the explosion chamber casing and the opening in the supporting member.

65 7. In an electric switch of the liquid break

type, an insulator bushing having a conductor stud therein, an adapter secured thereto said stud and adapter each having a gas discharge passage therethrough, an explosion chamber casing, a fixed contact, a detachable carrier enclosing the contact and forming one end of the explosion chamber casing, and bolts for firmly clamping the carrier between the adapter and the casing, said carrier having a gas discharge passage therethrough connecting at opposite ends respectively with the interior of the explosion chamber casing and the passage through the adapter.

8. In an electric switch of the liquid break type, a contact supporting member having a gas discharge passage therethrough, an explosion chamber casing, a contact carrier secured between the supporting member and the casing, and a fixed contact therein, said carrier having a gas discharge passage therethrough arranged to convey gas from the explosion chamber past and out of contact with the fixed contact to the passage in the supporting member.

In witness whereof, I have hereunto set my hand this 25th day of May, 1928.

CHARLES F. SCHWENNKER.
